VENETIAN BLIND

Robert B. Evans, Grosse Pointe, Mich.

Application December 30, 1942, Serial No. 470,581

26 Claims. (Cl. 160—168)

This invention relates to Venetian blinds or to shades or screens of this type, and its primary objects are to provide an improved blind in which the design and also the operation are materially simplified, so that while it is capable of all necessary or desirable operations, yet the total number of parts, including all fittings and the like, is reduced to a minimum; to provide a blind in which no hardware at all is required, so that, if necessary or desirable as in the present war emergency, no metal parts, even tacks or the like, need be used, and also lesser amounts of cord and textile materials are required; to provide a blind which, due to its simplicity, is cheap to manufacture and also saves the ultimate customer since he may buy it as a package of the right lengths and number of slats, flexible holders and cord to fit his window and readily put it together and install it himself; to provide an easily installed blind of this type which is also convenient and easy to take down and take apart for cleaning; and to provide an improved Venetian blind in which the whole blind, including all operating cords or the like, is suspended from the top rail which is, in turn, tiltably mounted so that it and the rest of the blind suspended therefrom can be conveniently put in place or removed.

In the usual types of Venetian blinds, in addition to the cords for collapsing the slats, there are other cords or some other means to tip or tilt the slats. It is an object of this invention to eliminate the necessity for such extra tilting means and to provide a single means for both of these functions, particularly a single or unitary flexible means such as a cord or cords to raise and collapse the slats and also to tilt them or hold them in tilted positions.

Also in the usual type of Venetian blinds, as mentioned above, the series of slats rests on offset rungs of a tape ladder suspended from a top member which has hardware or metal end pivots which are held in metal brackets fixed to the window frame or on a top cross member which is secured to the window frame, and its two spaced hoist cords extend from the lowermost rail or slat up through transversely elongated slots in the slats to pulleys, sheaves or the like on the tiltable top member and then to other pulleys or the like on the upper side portion of the window frame or jambs, and thence down the side of the jambs to be secured. Accordingly, it is an object of the present invention to have the unitary cord means not only collapsibly hoist the slats but prevent endwise displacement of the slats,

and also serve to tilt the slats or hold them in their horizontal or tilted positions and, in addition, serve as a stop or guide to prevent the blind from swinging or being swayed by the wind outwardly or away from the window or its frame. Thus, according to my invention, there may be only a single centrally positioned hoist and tilt cord or, if desired, two or more such cords or lengths spaced apart, which may, if desired, be under the ladder tapes, as usual; but my cord or cords slidably engage the top rail or some laterally offset part thereon to form a tilting lever. This may be done, for example, by passing the cord up through a hole through the top rail and then over its top face and directly down along, and normally engaging, the front or outer face of the blind to restrain it from swaying, the lower end of the cord being adjustably secured at or adjacent the window sill. Thus, the whole blind is flexibly suspended from a removable tiltably mounted top rail which may be mounted on the inside or outside of the window or the like, and there are no pulleys, guides or the like on the upper portion of the window frame, and the top rail itself acts as a cord actuating tilting lever. While the lower or secured portion of the cord or cords may be left free, they may also be connected to the bottom rail, or integral with or knotted to the cord portion extending down through the slats to form a closed loop, thus preventing the unsightly piling up of the cord when the blind is collapsed. Also, if desired, the single cord or the spaced-apart cord lengths may have integral or connected lengths of anti-sway and tilting cord extending down along both faces of the blind to thus tilt the blind in either direction from the horizontal and to restrain sway in either direction. Preferably, part or all of the weight of the bottom rail is carried by engaging a knot or other removable abutment on the hoist cord which has an upper knot or abutment engaging the top rail to prevent the cord from slipping, to thus space the bottom rail from the sill and make the blind of the right height, and to provide a normal tension in the seat engaging hoist cord to always hold the slats against endwise displacements. Preferably, the hoist cord receiving opening in the bottom rail has a square shouldered countersunk opening to receive the knot or the like with a slot opening in from the side for ready removal of the cord.

It is another object of this invention to provide improved hardwareless and readily removable pivotal mounting for the top rail which will also permit the top rail to extend full length be-

tween the side jambs of the window frame. Thus, I am eliminating the above mentioned usual pivots fixed on the ends of the top rail to be received in metal brackets mounted on the window jambs, by providing pivot pins (which may be short lengths of wooden dowel pins or the like to save metal as at present) fixed into suitable holes drilled in the upper side jambs and removably received in bearing-forming openings cut into the ends of the wooden top rail, both or only one of these openings having a preferably narrow throat opening through the bottom face of the rail so that the rail, with its suspended slats, may be easily set down on or lifted off these pivot pins. In this connection, I may provide a closure or gate means for the pivot entry throat or throats to prevent the top rail coming off the pivots in case it is tilted too far or too hard.

In another form the bearing opening may be elongated transversely of the top rail or enlarged so that it may partake of a combined sliding and pivotal movement as it tilts and slides along this track which may be straight or preferably curved or a cam track which may be of various curvatures and designs, although at present I prefer to provide a downwardly concave track or cam slot so that the blind will more readily remain in its horizontal position under the influences of gravity and friction and may be tilted in either direction (as by cords) so that the top rail and the suspended blind slides along the pivots to occupy the ends of these cam slots or enlarged bearing openings. Thus, by properly proportioning the parts, the blind may be made to stay in its horizontal or either tilted position without being held there in which case it would be unnecessary to adjustably secure the lower portions of the tilt cord except for the anti-sway feature. Further, I may use a simple, enlarged, round hole for this bearing opening to give a lateral movement of the top rail as it tilts and such a hole may be bored or drilled, instead of being routed.

In connection with the adjustable securing of the lower portions of this hoist and tilt cord, I have provided several simple arrangements, although I contemplate that any of the many known or suitable cord or top-gripping devices may be employed here.

It is another object of this invention to provide an improved form of slat-holding flexible ladder with fastening means to secure it to the end rails. In the usual Venetian blinds, the wide tape ladders are secured to the top and bottom rails by staples, tacks, or the like, and slat-holding rungs are alternately offset to permit the hoist cord to pass therebetween; while in the simpler forms of my invention the flexible ladder may be entirely of cord or of tape. In any case, it is secured by having either the cross rungs or the side portions of the flexible ladder pinched and thus firmly and removably held in narrow grooves or slots in the top and bottom rails, thus requiring no extra parts. Where I use only a single central hoist and tilt cord, or where several such cords are not concealed under the flexible ladders, the wide tape ladders with the alternate offset rungs are not necessary, so that I may use a ladder of cord or tape with no offset rungs. Of course, if desired, the combined hoist and tilt cords may be concealed under the usual wide tapes which may be secured by being pinched into slots, as noted above.

Other and more detailed objects and advantages, features or inherent capabilities will be apparent from the appended claims, from the fol-

lowing more detailed description of the invention and modifications thereof, and the accompanying drawings, in which:

Fig. 1 is a front elevation of a window frame with a mounted Venetian blind in accordance with this invention;

Fig. 2 is a section taken on the line 2—2 of Fig. 1 shown in larger size and with portions broken away;

Fig. 3 is a view similar to Fig. 2 but showing the blind held in tilted position;

Fig. 3a is a view similar to Fig. 3 but showing the bearing openings laterally offset so that the blind is normally tilted, as shown;

Fig. 4 is a top plan view of the mounted top rail with portions broken away;

Fig. 5 is a section on the line 5—5 of Fig. 4;

Fig. 6 is a top plan view of the bottom rail with portions broken away;

Fig. 7 is a section taken on the line 7—7 of Fig. 6;

Fig. 8 is a partly broken away plan view of one of the slats;

Fig. 9 is a view similar to Fig. 1 showing certain modifications in another embodiment of this invention;

Fig. 10 is an enlarged partially broken away sectional view taken on the line 10—10 of Fig. 9;

Fig. 11 is a partial section taken on the line 11—11 of Fig. 9;

Fig. 12 is a section taken on the line 12—12 of Fig. 9;

Fig. 13 is an enlarged detail elevational view showing the rope grip more clearly;

Fig. 14 is a sectional view of the top rail taken on the line 14—14 of Fig. 10;

Fig. 15 is a view similar to Fig. 1 showing certain modifications in a third embodiment of this invention;

Fig. 15a is a view similar to the upper portion of Fig. 15 but showing the use of knots 227;

Fig. 16 is an enlarged, partially broken away sectional view on the line 16—16 of Fig. 15; and

Fig. 17 is a section taken on the line 17—17 of Fig. 15.

Referring in more detail to the drawings, the first embodiment selected to illustrate this invention is shown in connection with a conventional window and frame comprising the usual side frame parts or jambs 1 and 2 preferably with the sash or casement guide pieces 3 and 4 on their facing inner sides (to normally engage the inner side or face of the blind), the sill or bottom member 5 and the lintel stop or top member 6.

The blind comprises a series of slats 10 which may be of various materials, including metal, plastic, paper, etc., as known in the art, and of various forms and shapes within the purview of this invention; but preferably they are painted or natural finished wooden slats. Similarly, the heavier end slats or the tilttable top rail 12 and the bottom rail 13 may be of various materials and shapes, but preferably are of wood, as shown, and are the same length and width as the slats, but are considerably thicker and heavier, the weight of the flexibly suspended bottom rail 13 aiding and holding the blind in its proper horizontal, tilted, or partly raised positions and aiding in holding the slats against lateral or endwise displacement, as hereinafter explained. Obviously, the extra thickness and strength of these end slats provide for the several slots and recesses therein without unduly weakening them, and permit the top rail to carry the rest

of the blind. Preferably, but not necessarily, the top and bottom rails 12 and 13 are identical, except for or before they receive their recesses and/or the like. As shown in Fig. 2, the cross section of the end rails 12 and 13 is generally rectangular, with the inner and outer edges or sides symmetrically rounded or curved on arcs of a circle, or other suitable curvatures, as shown at 15, to thus give a more pleasing effect by the rounded corners, to give a better tilting action as the flexible ladders and the cords wind and unwind on opposite sides as the slats and rails are tilted by preventing too sharp a bending of these flexible members and by somewhat reducing the change in the distance between the two vertical runs or sides of the flexible ladders as the blind is tilted. However, it will be appreciated that the precise forms of these end rails may be materially changed within the broader purview of my invention. For example, I contemplate that the bottom rail may be omitted in some designs and that the top rail may be round or of other shapes.

The spaced-apart or flexible ladders to support the slats in spaced relation and permit their tilting are preferably made of cord or twine, as shown in Figs. 1, 2 and 3, or they may be of narrow or the usual wide tape, as shown in Fig. 9 and Fig. 15. The cord ladder side portions 14 have the cord cross rungs 16 secured thereto in any desired or conventional manner, as by being woven, braided or twisted in to the side portions or by being knotted as at 16a to the side portions 14, all as will be well understood by those familiar with the forming of nets and other articles of cordage. As shown, the slats 10 merely rest on the flexible rungs 16 which are spaced apart vertically slightly less than the width of the slats. In one example which has proven satisfactory (the embodiment shown in Figs. 1 to 8 inclusive) the slats are 2 inches wide, the width of the rungs or the spaces between the sides of the ladder is $\frac{1}{8}$ inch greater than the width of the slats, and the vertical spacing of the slats is $\frac{3}{8}$ inch less than the slat width. The cord of the ladder parts 14 and 16 is twisted corded twine comparable with No. 16 medium grade Seine twine.

The end slats 12 and 13 and the flexible ladders 14-16 are removably secured together by the narrow slots or grooves 17 which tightly receive the pinched end portions of the flexible ladders. When used, the knobs 16a will prevent slipping in these grooves. These slots 17 are spaced to match the desired positions of the ladders and are preferably milled into the wood of the rails, so as to extend transversely completely across the top face of the top rail and across the bottom face of the bottom rail. The depth of these slots 17 may vary but should be sufficient to firmly hold the ladder portions and, as shown here, is about one-half the thickness of the end rails, or $\frac{3}{8}$ of an inch. The width of these slots is such that the cords or tapes have to be forced into them to be tightly pinched. As will be understood, the wood will spring slightly to give an elastic spring action and a firm frictional grip. In this first embodiment, the width of the slots is .004". Since the slots 17 are on opposite sides of the end rails from the load on the cord portions 14, the bends in the cord around the sides of the end rails will give a sort of snubbing or frictional action to aid in holding the cords and prevent their pulling out.

In securing the ladders to the end rails, either

the end portions of the sides 14 of the ladder or the end cross rung 16 itself may be pinched into the slots. As shown, the slots 17 in the top rail receive the first rungs of the flexible ladder, while the slots 17 in the bottom rail receive the ends of the side rungs of the ladder, which may be overlapped if desired to take care of any excess length and to give a better grip. Also, carrying the bottom rail by the side rungs of the ladder permits the spacing of the bottom rail to be adjusted with respect to the next slat above it.

The bottom rail 13 has a centrally positioned hoist cord hole 18 extending therethrough from its top to its bottom face and having the countersunk bottom portion 19 opening in from its bottom face, with the preferably square cut or flat shoulders 20 which have been found to be important in properly holding the lower knot 26. Preferably, the hole 18 is the end of a routed-in slot 21 opening in from the back edge of the rail (the edge toward the window). The slot 21 extends from top to bottom of the rail and is only slightly wider than the hoist cord used, to thus permit the cord to be withdrawn from the bottom rail without untieing the end knot 26. This has been found to make the assembly and take down considerably more convenient, as the knot 26 can be more easily untied when the cord is withdrawn from the bottom rail and also the knot can be more accurately positioned when it can be tied in the cord while alongside of the bottom rail and then slid into place.

The top rail 12 has a similar or corresponding hole 22 extending from its top to its bottom face and having the upper countersunk or enlarged knot-receiving portion 23 which may be cut in various ways, for example with the sloping shoulders, as shown. For one hoist cord, hole 22 is positioned centrally of the length of the top rail, and while hole 22 may be positioned centrally of the width of the top rail, yet where, as in this particular embodiment, the blind can be held in only one extreme tilted position as by the tilt cord coming down only on the outer face of the blind, I prefer to have hole 22 offset toward the front or outer edge of the top rail, as shown, particularly when no closures, such as plugs 40 are used since this offset helps to prevent the rail coming off the pivots.

The cord 25 has a plurality of functions. It serves as the hoist cord to collapse the slats by raising them from the bottom rail; it serves to tilt the slats and hold them in tilted position; it holds the slats in alignment against endwise movements since the portion of the cord passing through the slots 24 is always tensioned and thus will restrain or engage the edges of the slots 24 upon any appreciable endwise movements of the slats. Further, when its lower end or lower portion is secured, that portion of the cord extending down along the front (or the back) face of the blind will prevent the blind from swinging laterally out from the window on its frame. It will be understood that normally the blind, particularly when its slats are in horizontal position, will rest against and be engaged with portions of the window frame, such as 3 and 4, or else with the window itself, so that the blind cannot swing inwardly towards the window. Also, the secured cord portion extending along the outer face of the blind will prevent it from swinging outward, since when the slats are horizontal, this outer secured cord portion will normally engage them, and when the slats are tilted there may be a

little clearance, but no appreciable swinging or swaying movement of the blind will be permitted. In assembling the blind for installation, the cord 25 is passed through the slots 24 of the aligned slats (which may be inserted beneath flexible ladders which are mounted on the installed top rail), and the knots 26 and 27 are then tied. Preferably, the knot 26 is tied first at or adjacent one end of the cord, the cord is threaded through slots 24, and the knot 27 is then tied and spaced at the proper distance to position the bottom rail properly above the sill 5 to determine the desired height of the blind, and particularly so that the cord 25 carries part or all of the weight of the bottom rail 13. Thus, the portion of the cord 25 passing through the slots 24 of the slats will always be tensioned. Of course, all or only part of the weight of 13 may be thus carried, so long as there is sufficient tension in the cord 25 to hold the slats against endwise movements.

Thus, as shown in Fig. 1, the knots 26 and 27 of the cord 25 support part of the weight of the bottom rail 13 when the slats are in horizontal, tilted, or collapsed positions, so that the portion of the cord between these knots will engage the sides of the slots 24, which are not very much wider than the cord, to thus prevent any appreciable endwise displacement of the slats. It will, of course, be understood that the cord, slats and end rails may be assembled in various ways. For example, the knot 26 can be tied first, the other end of the cord fed through, and the remaining knots then tied.

It will be seen that in taking the blind down, as for cleaning, it will only be necessary to untie the knot 26 in order to completely remove all the slats and the end rails. As explained above, the knot 26 can be more accurately positioned at just the right point on the bottom rail because of the open throat 21.

After the cord 25 is threaded through the slats and knots 26 and 27 are tied, the series of knots 28, 29 and 30 are tied in their proper positions, which can be readily determined by trial with the blind in place. These knots are removably engaged and held by securing means 31-31 to thus hold the blind in various tilted or collapsed positions. To avoid the use of any hardware, the securing means may, as shown here, be in the form of two wooden dowel pins 31-31 which are driven into holes suitably bored in the sill 5 and spaced apart just enough to pass the cord 25 but to grip the knots or other projections thereon.

This type of securing means for the cord embodying fixed abutments or walls to engage a knot or other projection on the cord, has certain advantages since it gives a positive, non-slip grip and will cause less fraying or wearing of the cord (particularly if a cheaper type of cord is used) than certain other types of cord securing means which may be used, such as a spring or friction clamp or grip to pinch the cord and thus hold it in any desired position without any knots or other projections.

It is within the broader purview of my invention to employ, in lieu of knots such as 26, 27, 28, 29 and 30 or the similar knots in the other embodiments, other forms of projections on the cords such as molded-on projections of plastic or the like, clamped or clipped on projections, and others as will be known or apparent to those skilled in such arts. The projection 26 should be removable while the others may be removable

or else permanently secured once the cord is made up in the factory or home for a particular blind installation.

The last or end knot 30 is positioned to hold the slats in extreme tilted position; that is, in the embodiment shown, with the outer edges of the slats tilted down while the knot 29 will hold the slats in intermediate or half-collapsed position, and the knot 28 will hold them in fully collapsed position. Obviously, more knots may be provided if more adjusting positions are desired. It will be understood that in assembling the blind the end knot 26 may be tied loosely or without pulling it up tight, so that later this end knot 26 may be accurately positioned by sliding the cord out through the throat 21 and adjusting the final position of the knot.

After passing through the hole 22 in the top rail, the cord is turned over the top of the top rail and comes directly down the outer or front side of the blind to be adjustably secured as just explained. It will be noted that this blind requires no pulleys, guides, sheaves or the like for the cord to be mounted in the upper portion of the window frame, and it will be seen that the cord, by passing through and over and thus engaging the top rail itself, makes use of the top rail as a lever arm for tilting the same. It will, of course, be apparent that this may be accomplished in other ways by having the cord engage parts or members carried by the top rail. As shown, it will be apparent that this effective lever arm has a length of one-half of the width of the top rail, although it will be apparent that this may be varied if desired.

The top rail is readily removably and tiltably mounted on the pivots 37, which in this particular embodiment are two short two-inch lengths of wooden dowel pins which are of Port Orford cedar and $25/64$ " in diameter and are tightly driven into slightly smaller holes suitably drilled or bored at the desired point of suspension by the householder, with one inch protruding. The opposite ends of the top rail have pivot-receiving bearing openings 35 in the form of end slots which also open out through the bottom face of the top rail, so that the rail may be readily installed or removed by being set down on or lifted up from the fixed pivot pins.

In this first specific embodiment, the openings 35 simply supply easy or loose bearings for the pivots 37 and with the pivot center offset upwardly from the center of the top rail, and in operation, the arrangement and the weight of the suspended blind will cause the blind, when unrestrained, to merely return to or nearly to its horizontal slat or untilted position. Thus the blind must be held in the extreme tilted position and will return to the horizontal, except for the effect of friction in the bearings, which last is not particularly important as the slats may be set in the horizontal position or in desired slightly or partly tilted positions by manually moving the bottom rail, the ladders, or the hoist-tilt cord.

Preferably, these slots 35 have a keyhole-type cross section or an enlarged inner partly circular portion (here it is specifically $15/32$ " diameter) to form an easy or loose fitting bearing for the pivots and so that the narrower entrance throat 36 has a relatively close fit just sufficient to pass the pivot dowels 37, to thus permit free tilting of the top rail and to prevent the rail from being tilted too far, so that the pins will come out of the throat 36. Slots 35, 36 may be routed into the wood of the top rail. Thus, this relatively

narrow throat aids in preventing the top rail coming off the pivots when the cord is pulled too hard. It will, of course, be understood that different forms of pivots and bearings may be employed. Obviously, pivots of strong material, such as metal pins when available, may be of smaller diameter and the bearing opening will also be correspondingly smaller.

While the top rail will generally stay on its pivot pins 37 in ordinary usage in raising the blind, yet in order to prevent the top rail being accidentally pulled off due, for example, to too hard or quick a pull on the cord so that the top rail is bounced up or tilted too far, I may, if desired, provide a simple removable closure or gate to prevent the rail from accidentally coming off and yet to permit the blind to be easily taken down, as for cleaning. Thus, I may employ a removable closure plug 40 which is pushed into the throat 36, as from the bottom face of the rail. As shown, these wooden plugs 40 are of a generally rectangular shape and are arranged to be readily removed and yet to fit tightly in this throat by a tight frictional fit or by slightly springing apart its wooden sides with a wedge action. While a plain tight friction fit will suffice preferably the plugs are given a slight taper or wedge shape so that the inner face 31 which lies along the pin 37 is slightly narrower than the exposed face 32 for easy entrance and a wedge action to give a frictional fit. Also, this plug may be slightly tapered longitudinally so that its outer end 43 is slightly wider laterally than its inner end 44 to give a tight or wedge fit. Of course, it will be understood that other designs of closures may be employed here, including the gate shown in Fig. 15.

It will be seen that the top rail 12 and its suspended slats can only be tilted in one direction or with the inner slat edges pointing down when only one pull cord is used and the bearings 35 are positioned centrally of the width of the top rail, as shown. However, this arrangement may be readily modified, as shown in Fig. 3a, so that the same bearing openings 35' are offset laterally toward the front or outer edge of the top rail so that it will normally hang in extreme tilted position, with its inner edge up, as shown in Fig. 3a where the cord 25' is loose or untensioned and the suspended slats will be tilted. Thus, the one cord length on the outer face may then be employed to hold the top rail and slats in intermediate tilted positions, in horizontal position or in the other extreme tilted position, and further pull on this same cord will start to collapse the blind in its second extreme tilted angular position. It will be apparent that the cord may be held by the pegs 31 and a suitable number of knots, as in Fig. 1, or by some other suitable cord grip device.

It will also be seen that my simple, hardware-less, removable pivotal mounting which is formed in part by the wood or material of the top rail itself also permits the top rail to be of full length; that is, it can extend the full distance between the side jambs so that it lightly engages them or nearly engages them, thus permitting a neater installation and making measurements for fitting by the householder considerably easier. Also, no header board or the like is necessary and no special or separate tilting mechanism is required.

As will be apparent, the several blinds of this invention also may be full length and mounted in doors or other openings, they may be mounted on the outside of windows or other openings, and

the several drawings may be considered as also showing such outside mountings with the front face or edges being considered as the outer face or edges. Also, where the window frame is not wide enough for proper positioning of the pivots, I may, of course, attach suitable brackets or the like to carry the pivots, all as is well known in this art.

Summarizing the installation, a blind having been purchased as a knock-down package with the right number of lengths of slats, end rails, and lengths of flexible ladders and hoist tilt cord, the holes 38 are drilled in proper positions just enough below the lintel top 6 to permit sufficient tilt of the top rail 12 when the pins 37 are driven in. Properly spaced holes for the pins 31 may be drilled and these pins forced in. It will be noted that these operations can be done in any order.

20 The slats are slipped in between the rungs of the flexible ladders and the upper and lower ends of the ladders are secured to the top and bottom rails in their grooves 17, as previously described. With the slats aligned and, if desired, compacted, the cord 25 is fitted through their slots 24, and the knot 26 may be tentatively or loosely tied. Then the top rail 12 is set down on its pivots and the knot 27 is tied at the correct position, or, if desired, the top rail may be mounted with the flexible ladders attached and the slats and hoist tilt cord then put into position. As mentioned, the knot 26 may be moved or used to make a final adjustment of height and tension here. Then the other tilted and raised position knots such as 28, 29, 30 are tied in their proper positions, as determined by test, and the installation is complete. It will be apparent that removal is substantially the reverse of these operations; however, only knot 26 need be undone in order to slip out all of the slats for thorough cleaning or the like.

40 In Figs. 9 to 14, illustrating certain modifications in a second embodiment of this invention, the several parts are the same as in the first embodiment except as otherwise noted and the reference numbers for parts which have similar functions or are analogous to those of the first embodiment are the same plus 100. In these figures, the slat 110, the bottom rail 113 and the pivots 137 are the same as the corresponding parts are in the first modification.

45 The flexible ladders may be in the form of the ladders of narrow tape (1/2" wide as shown) with the sides 114 and the non-offset cross rungs 116, these ladders being secured into grooves 117 with two end rails as described above for ladders 14-16. It will be apparent that either the tape ladder sides or rungs can be pinched into slots 117 which will be of the proper width.

50 Only one central hoist-tilt cord is shown as in Figs. 1 to 8, but as illustrated here, the otherwise similar hole 122 in the top rail 112 is also centered between the back and front edges of the rail, particularly since in this second modification, the blind slats may be horizontal or be tilted to extreme position in either direction while they are fully extended by having the hoist tilt cord, such as 125, include a portion 125a extending down along the other face or back of the blind to be adjustably secured like the portion extending down the front of the blind as described above. Thus, it will be seen that by the use of hoist-tilt cord portions down both faces there is provided a blind which is biased so that it normally returns to or nearly to the horizontal slot position as in Fig. 1 and which may be tilted

to the extent desired in either direction by pulling down the appropriate cord portion 125 or 125a and the blind may be tilted or collapsed by either handling cord portion.

Also the portion 125a, when secured and tensioned, will serve to restrain the blind against swaying or swinging in this direction and, as shown, the blind may be restrained against swinging in either direction or thus held in both directions when both handling cord portions are tensioned as when the blind is lowered or partly raised. Cord portion 125a will be desirable for this reason where the blind does not normally rest against guide surface such as window frame portions 3 and 4.

The portion 125a may be made in various ways, for example, it may be knotted into the cord 125 at the knot 127, or above this knot as shown at 127a. Also as shown here, the loose free end or ends of the hoist-tilt cord, which would as shown in Fig. 1, pile up on the floor as the blind was collapsed, may be eliminated by forming, in effect, a closed loop. Thus, the free ends of the cords may be secured to the lower face of the bottom rail 113, or preferably and as shown, these ends are knotted as at 126a to the lower end of the cord 125, below knot 126, so that as the blind is raised or collapsed by 125 or 125a, or both, the otherwise free ends of the cord being raised to prevent loose or piled up ends.

In lieu of knots or other projections or the like on the hoist-tilt cord to give a definite and limited number of tilted and raised positions as in Fig. 1, we may, as shown here, omit all holding knots or the like on the cord 125, except, of course, for the knots 126 and 127, and if desired, knots 126a and 127a. In this case, the cord may be held in any one of an infinite number of adjusted positions of tilt or collapse for the blind, by a suitable cord or rope gripping device which may be any one of the various known types or of the design shown at 131. This cord grip, indicated as a whole by 131 and which may be of plastic, metal or wood, is screwed down on the window sill as shown, and is formed to have a generally horizontal but slightly upwardly directed and inwardly converging slot 132 opening from one side. As will be apparent, either or both cord portions 125 and 125a may be passed through this slot from opposite sides, as shown in Fig. 10. The upward pull on the cords will tightly pinch them into this upwardly directed and tapering or converging slot or groove 132, which has rounded sides or edges to reduce wear or fraying of the cords. Preferably, the cord portions are long enough so that there are slack or loose portions between grip 131 and the knot 126a. As will be seen, the width of slot 132 is about equal to or preferably slightly less than the width of the bottom rail so that the cords will extend straight up.

In the top rail pivotal mounting of Fig. 1, the openings 35 are upwardly offset and are merely loose or easy bearings for the pivots, so that when unrestrained, the blind is normally biased to return toward its horizontal slat position and thus must be held in slat tilted positions. However, in the present embodiment I show one form of a preferred pivotal mounting for the top rail or other top member to give a combined pivotal and lateral sliding motion to the top rail as it is tilted. Thus I may more readily obtain large tilt angles and I may also arrange or pro-

portion this type of pivotal mounting so that the top rail and the suspended slats will normally remain in any desired or adjusted tilted position, even when the cords 125 or 125a are not tensioned. Upon reflection, it will become apparent that these results may be accomplished in various ways. As shown here, the bearing openings 135 are laterally enlarged or elongated relative to the pivot pin size and the top or upper

surfaces of the bearing provides a laterally extending track or preferably a downwardly concave curved cam surface for the pivot. Preferably opening 135 is a round hole so it can be bored or drilled, which is easier than routing. Specifically, here the $\frac{3}{4}$ " thick top rail 112 has hole 135 of $\frac{5}{8}$ " diameter for the same $2\frac{3}{4}$ " diameter pivots as shown in Fig. 1. As will be seen, the bearings 135 are relatively larger than bearings 35. Various proportions may be used for different types and designs of blinds, and the specific proportions are given here to give a clearer understanding of certain satisfactory designs.

As the top rail is tilted either way by a pull on the ladders, on the slats, or on the cords 125 or 125a, the top rail will also shift or slide laterally as it tilts so that its center of gravity and that of the suspended blind is offset laterally with respect to the pivots.

The curvation of the top surface of the opening 135 or the relative curvatures of 135 and 131 may be such, as illustrated here, that the blind will stay in any tilted position, due to this lateral offset or sliding action, the weight of the suspended blind and friction in the bearings.

In order to reduce the possibility of the top rail 112 being pulled off its pivots, I may make one end bearing without any side or bottom entrance throat and the other bearing will have such a throat. Thus, instead of two such throats, as in Fig. 1, where the top rail can be simply set straight down on its pivots, here I will first place the loose and entirely closed or non-throat bearing 135 over its pivot pin and then set the other bearing down on its pin through its entry slot or throat 136, which will just pass the pin 131 as described above. Although I may employ a closure for the entry throat, yet, because of the much smaller possibility of accidental removal of the top rail, I do not illustrate such a closure in this particular embodiment.

The installation and the operation of this embodiment will be generally similar to that of Fig. 1, except for the above noted or apparent differences.

In Figs. 15 to 17, illustrating certain other modifications in a third embodiment of the invention, the several parts are the same as in the previous embodiment, except as otherwise noted, and the reference characters for parts which have similar functions to those of the first embodiment are the same plus 200.

Particularly in the case of wider blinds, it may be desirable to employ two or more spaced hoist-tilt cords or rail engaging cord portions, such as the two legs of cord 225. While retaining a number of the features and advantages of this invention, it is also possible to have these hoist-tilt portions 225 mounted under and concealed by the conventional wide tape ladders 214 and between the usual offset narrower tape rungs 216, as is conventional in the installation of the usual spaced simple hoist cords. Although it will be apparent that the hoist-tilt cord here may be made up of several pieces or lengths suitably con-

nected by knots or otherwise, I prefer to have the main portion consist of only one length 225, which may be considered as being in the form of an inverted U, with its legs extending down through and engaging the sides of the laterally elongated slots 224 (to thus restrain the slats against end-wise movements when these cord portions are tensioned, as described above), and with the lower ends of the U or the free ends of the cord knotted as at 226 to be received in openings 218 having the portions 219 and 220 and the side or back entry throat 221 all as explained in connection with the embodiment of Fig. 1. The legs of the U of this cord 225 pass between the conventional alternately offset narrow tape rungs 216 and then through the spaced top rail holes 222 which are positioned centrally above the centers of the ladders. However, the top of the inverted U of this cord lies along and engages the portion of the top rail between the holes 222 so that, as shown in Fig. 14, upper knots are not essential here to hold the bottom rail and to always tension the cord 225 by reason of the lower end knots 226. However, as an aid in getting the two sides of the blind of equal height, I may employ knots 227 to engage in these holes 222, as shown in Fig. 15a, as the knot 27 engages in hole 22.

If desired, the ladders 214 may be secured to the rails by pinching grooves 217 as shown in the embodiment of Fig. 1. Here, however, the grooves 217 in the top and bottom rails are offset slightly to one side or the other from holes 222 or from the centers of the tapes to conform to the offset narrow tape rungs 216 which are tightly pinched into these grooves, for example, by being forced into the grooves by a knife edge or the like. In order to get the proper spacing between the adjacent slats and the end rails, I may, as shown, centrally cut the end cross rungs 216 of the ladder so that the ends are separated when in grooves 217, thus getting the same effect as though the end rungs of the ladder were wider spaced than the other rungs to conform to the greater thickness of the end rails.

While this third embodiment may be designed like the first embodiment with similar pivot bearings and the cord or cords to give a one-way tilt or to pull only on one edge of the top rail, yet I prefer to have suitably attached hoist-tilt cord portions extending both down the front and back sides of the blind so that it may be secured against accidental dislodgment in any desired tilted or raised position and normally held in its central or horizontal position.

Instead of having spaced cords extending down in front and back or outside of the ladder tapes, I prefer to have one or a single length of cord 225a suitably attached to cord 225 intermediate, and preferably centrally between, the holes 222 by suitable knots such as 227a, whereby the free ends of this cord 225a are knotted together and to cord 225, leaving a closed loop or bight hanging down below and around the bottom rail 213, there being sufficient slack so that either or both sides or runs may be adjustably secured in a suitable rope grip member, such as 231, which may be identical to 131. Thus I have illustrated here a somewhat different form of closed loop than the one shown in the second embodiment, since here, instead of being attached to the bottom rail or to the portions of the cord coming down through the slats, the handling cord portions are connected to each other to form a closed loop hanging free and running under the bottom rail. 75

As the blind is raised or collapsed, the inverted U top of cord 225 will change from a straight length into a V form with a decreasing apex angle which will be on one face, or the other, depending on which handling cord is pulled.

Thus, as in the second embodiment, the blind here may be tilted or held tilted in either direction and may be raised by either of the handling cord portions. While the blind is partly raised or collapsed, I may tension both the inner and outer handling cord portions by passing two turns of the cord through the grip member 231 from opposite sides.

In connection with this third embodiment, I have illustrated another possible variant of a pivot bearing to give combined sliding and tilting motion. Here opening 235 is in the form of a laterally elongated slot with rounded ends and a flat top 235a parallel to the faces of the rail which has a centrally located part cylindrical recess 235b, which will receive and thus hold the pivot pin to normally retain the blind in its horizontal or nearly horizontal position. Upon a certain amount of tilting, the recess 235 will come off the pin 237 and the top rail will move laterally until the pivot pin 237 is held in the rounded end of the slot. Thus, in this particular design, a blind may be horizontal or slightly tilted in either direction and then will go to either extreme tilted position. It will be apparent that this blind will remain in its horizontal or nearly horizontal position or in its extreme tilted positions without being otherwise retained, as explained in connection with the previous embodiment. Here, as in the second embodiment, I have shown the bearing opening 235 at one end as being closed, while the opening at the other end has the pivot entry throat 236, so that the top rail is installed as explained in connection with the second embodiment.

It will be seen that pivot pins are offset above the entry plane of the top rail in all of the embodiments shown to get a more stable mounting and that in all forms shown the bottom rails 45 may be identical with the top rails except for the different openings. Obviously, the top rails may be thicker to provide more room for the bearings and the bottom rails may be quite thin, or only slats, if the cord tensioning feature is not desired.

If desired, I may employ a closure for this entry throat 236 which may be in the form of a swinging gate consisting of a plate 240 of any suitable material swingable on a pivot pin 246, so that it may be moved from open to closed position and may be retained closed by means such as a detent 247, or merely by having the pivot pin (which may be a nail or screw) pressed in tightly enough to give sufficient friction.

As will be apparent, the blinds of the second and third embodiments may be tilted or raised by pulling on the inner or outer handling cord portions. Also, I intend to include several connected cords when I refer to a cord or a common cord or the like in the claims or elsewhere herein, unless I specify otherwise.

As will be apparent, the installation and operation here are essentially the same as in the previous embodiment, with the differences being noted above, or obvious.

It will also be understood by those skilled in this art that the several features and modifications illustrated here may be used in the other embodiments shown here or may be employed in various other combinations, and that the several illustrated embodiments of this invention are not

intended as limiting, since the invention may comprehend various arrangements, modifications, and other features without departing from the spirit and teachings of this disclosure or the scope of the appended claims.

I claim:

1. In a Venetian blind having a series of slats, spaced apart flexible ladders to suspend said slats, means to bias said slats to tilt in one direction, and a common flexible means to raise or lower said slats and also to tilt them in the other direction.

2. A Venetian blind comprising, in combination, a series of slats, flexible means to suspend said slats in spaced relation, and means including only a single cord to tilt, to raise or lower said slats, and to hold them in tilted or in raised positions.

3. In combination, a Venetian blind comprising a series of slats, flexible means to suspend said slats, a second flexible means to tilt said slats, and means to always tension said second flexible means to hold said slats against lateral movements.

4. A Venetian blind comprising, in combination, a tiltably mounted top rail, a series of slats, flexible means suspending said slats in spaced relation from said top rail to be tilted therewith, and a common flexible means to hold said slats against endwise displacements and against lateral swinging, to hoist and collapse said slats, and to tilt said slats.

5. A Venetian blind comprising a series of slats, means to flexibly suspend said slats in spaced relation, a common hoist cord means to raise and collapse said slats and means to tension said hoist cord means when said blind is lowered or raised to always hold said slats against lateral displacements.

6. A Venetian blind comprising a series of flexibly suspended spaced slats having aligned openings therethrough and a hoist cord through and engaging the sides of said openings and having spaced means thereon engaging the upper and lower slat members and always maintaining the cord in tension by at least part of the weight of the lower slat member, to thus restrain all of said slats from endwise displacements.

7. A Venetian blind comprising a tiltably mounted top rail, a series of spaced slats flexibly suspended therefrom to be tilted therewith, flexible means engaging all of said slats and to collapse said slats carried by and suspended only from said top rail, and means to always tension said flexible means to restrain said slats against lateral movements.

8. A Venetian blind comprising a tiltably mounted top rail, a series of slats, flexible means suspending said slats in spaced relation entirely from said top rail to be tilted therewith, flexible means suspended entirely from said top rail to tilt said top rail and said slats and to collapse said slats, whereby all of the operating members of said blind are supported only by said tiltably mounted top rail.

9. A Venetian blind comprising a tiltable top rail, means to pivotally mount said top rail in the window frame for tilting motions, a plurality of slats having openings therethrough, spaced apart flexible ladder means to suspend said slats in uniformly spaced parallel positions from said top rail to be tilted therewith, and a centrally positioned, flexible means to collapse and raise said slats suspended entirely from said tiltable top rail extending up through said openings and

down across one face of said blind engaging said slats and secured at its lower end to hold said blind against swinging.

10. A Venetian blind comprising a tiltably mounted top rail, a series of slats flexibly supported in spaced relation therefrom to be tilted therewith, and spaced apart flexible means to raise said slats carried by and suspended entirely from said tiltable top rail and having a portion secured at its lower end extending down along and engaging the exposed face of said blind to hold it against swinging.

11. A Venetian blind comprising a tiltably mounted top rail, a series of slats supported in spaced relation therefrom to be tilted therewith, and a common flexible means to tilt said rail and slats and to collapse said slats suspended only from said tiltable top rail.

12. A Venetian blind comprising a tiltably mounted top rail having a central hole therethrough, a series of slats flexibly suspended therefrom to be tilted therewith, said slats having aligned transverse slots therethrough, and a hoist cord secured to the lowermost slat member, extending up through and fitting loosely in the slots in said slats to permit tilting and through the hole in said top rail, and then extending over said top rail and directly down across and engaging the exposed face of said blind, and means to adjustably secure this lower portion of said cord to hold said blind in selected tilted positions and selectd raised and collapsed positions and also to restrain said blind from swinging.

13. As an article of manufacture, a wooden Venetian blind top rail to be tiltably mounted on opposed pivots fixed in a window frame or the like and to tiltably carry a series of slats, said top rail having a pivot receiving, bearing forming opening extending into the wood of said top rail from each end thereof.

14. A Venetian blind comprising a top rail, a series of slats, means flexibly suspending said slats in spaced relation from said top rail to be tilted therewith, and means to mount said top rail for pivotal tilting and lateral sliding movements comprising opposed pivot members secured in the window frame and a pivot receiving, bearing opening in the material of each end of said top rail itself, said openings being laterally enlarged with respect to said pivots to permit lateral sliding as the rail is tilted.

15. A Venetian blind installation in a window frame comprising a tiltable wooden top rail and a series of slats flexibly suspended therefrom to be tilted therewith, the tiltable mounting of said top rail comprising wooden pivot pins fixed in suitable holes in the window frame, and pivot receiving, bearing openings cut into the ends of said top rail, and also at least one opening through the bottom surface of said top rail, to thus avoid the necessity for hardware in the pivotal mounting and whereby the blind may be removably installed by positioning the top rail down on the pivots, and said bearing openings being laterally offset from center so that the top rail and blind are normally tilted when unrestrained.

16. In a Venetian blind installation in a window frame, pivot pins secured to said frame and a tiltable top rail having means for readily and removably mounting it on said pins comprising bearing openings loosely fitting said pins extending into the wood of its ends, and at least one of said openings having an open bottom

throat to pass said pivot pin, and a movable closure member for said throat.

17. A tilttable, one piece, wooden Venetian blind top rail having an open sided, pivot receiving, bearing slot forming recess extending into the wood of the end of the top rail itself.

18. A Venetian blind comprising a top rail, a series of slats, means flexibly suspending said slats in spaced relation from said top rail to be tilted therewith, and means to mount said top rail for combined tilting and lateral sliding motion in either direction from the open horizontal position of the top rail and the slats whereby friction and the weight of the blind will hold it in horizontal or tilted positions.

19. A Venetian blind comprising a top rail, a series of slats, means flexibly suspending said slats in spaced relation from said top rail to be tilted therewith, and means to mount said top rail for a combined tilting and lateral sliding motion, said mounting means being constructed and arranged to frictionally retain said top rail and the slats tilted therewith in any desired adjusted tilted or horizontal position.

20. A Venetian blind comprising a top rail, a series of slats, means flexibly suspending said slats in spaced relation from said top rail to be tilted therewith, and pivot means to mount said top rail for a combined tilting and lateral sliding motion in either direction from a central horizontal position including means to normally hold said top rail in its horizontal position.

21. In a Venetian blind, a top rail having transverse slots across its upper surface and suspended, slat holding, tape ladders tightly pinched therein.

22. A Venetian blind comprising a series of tilttable slats, flexible ladder members holding

said slats, and a tiltably mounted top rail having narrow grooves to pinch and thus secure upper end portions of said members.

23. As an article of manufacture, a Venetian blind end rail having narrow transverse grooves to pinch and thus secure the end portions of slat holding flexible members.

24. A Venetian blind comprising a tiltably mounted top rail, spaced cord ladder members, a series of slats removably held in said ladder members, said top rail having correspondingly spaced narrow grooves across its upper face to pinch and thus removably secure the upper portions of said suspended cord members.

25. A Venetian blind comprising a tiltably mounted top rail, a series of slats flexibly suspended therefrom to be tilted therewith, and a hoist cord to collapse said slats secured to the lowermost slat member, slidably suspended from said top rail and then extending down the exposed front face of the blind and connected to the portion secured to said lowermost slat member to form a closed loop, and means to secure the lower portion of said loop in selected positions to hold the blind in desired collapsed positions.

26. A Venetian blind comprising a tiltably mounted top rail, a series of slats flexibly suspended therefrom to be tilted therewith, a lower cord-securing means, and a slat-collapsing hoist cord means secured to the lowermost slat, slidably engaged over a portion of said tilttable top slat member and then extending directly down across the inner exposed face of said blind to said cord-securing means to hold the blind in selected collapsed positions and to restrain the blind against swaying.

ROBERT B. EVANS.
